UNITED STATES PATENT OFFICE.

GEORGE H. ROLFES, OF ST. LOUIS, MISSOURI, ASSIGNOR TO ALEXANDER H. HANDLAN,
OF ST. LOUIS, MISSOURI.

ADJUSTABLE REFLECTOR FOR LIGHTING DEVICES.

Application filed August 20, 1926. Serial No. 130,377.

My invention relates to an adjustable reflector for lighting devices, and has for its particular object the positioning of the reflector, together with the incandescent bulb 5 in the lighting device, in proper focal relationship with the lens at the forward side of said device. In order to properly locate the bulb and reflector with reference to the focal point of the lens universal adjustments must be made, both with respect to 10 the bulb and the reflector, to correlate these with respect to the focal position of the lens. My present invention relates more particularly to the universal adjustment of 15 the reflector, the bulb-adjusting means being embraced in another application heretofore filed.

Fig. I is a front elevation of my device.

Fig. II is a side elevation of the same. 20 Fig. III is a detail side elevation of the rear portion of my device showing the use of a liner strip, or shim, at the bottom portion thereof.

Fig. IV is a front view of the lower portion of the device shown in Fig. III.

1 designates a reflector of conventional type mounted in a supporting ring 2 which is split as shown at 3 and provided with outwardly turned ears 4, which are apertured 30 to receive a bolt 5 for drawing said ring 2 together when the reflector 1 is located therein. 6 are ears, preferably four in number, formed on the outer periphery of the ring 2 (see Fig. I) and are apertured 35 to receive screws 7 which serve to limit the movement of the ring 2 with respect to another member hereinafter to be described.

8 are adjustment screws also passing through apertures in the ears 6, and 9 are 40 springs surrounding said screws 8. 10 designates a supporting member, preferably ring-shaped, provided with forwardly projecting lugs 11, between the forward ends of which and the inner faces of the ears 6 45 the springs 9 surrounding the screws 8 are adapted to rest. These lugs 11 contain screw-threaded apertures, and the screws 8 are adapted to project into said screw-threaded apertures. The ring-shaped member 50 10 also contains preferably four screw-threaded apertures 12 normally located between the lugs 11. 13 designates the base or the rear end of a lighting device through which screws 14 are adapted to pass to seat 55 in the apertures 12 in the ring-shaped

member 10. Surrounding said screws and positioned between the ring-shaped member 10 and the end 13 are springs 15. 16 designates a supporting member attached to the bottom portion of the ring-shaped member 60 10 which projects forwardly and supports the incandescent bulb A and its associated universal adjustment members. As the adjustment means for the bulb A is the subject-matter of another application for Letters Patent, these members will not be 65 further described herein.

In the operation of my device the bulb A is first focused with respect to the reflector, after which the ring 2 carrying the 70 reflector 1 and the bulb A is placed in the lighting device at the point adapted to receive the same, and then the reflector is adjusted to properly locate the same with respect to the focal position of the lens (not 75 shown). By adjusting the screws 14 the ring or support 10 may be tilted or moved into any appropriate position, after which the reflector-supporting ring 2 may be adjusted by means of the screws 8, which pass 80 through the ears 6 into the threaded apertures in the lugs 11 located on the ring or support 10. When the proper focal position has been obtained with respect to the reflector the screws 7 are turned until contact is had with the surface of the ring 10, which holds said ring 2 positively in its adjusted position. The apertures through which the screws 7 pass in the ring 2 are 85 screw-threaded to permit of the inner 90 and outer adjustment of these screws. The springs 9 located between the ends of the lugs 11 on the ring 10 and the ears 6 on the reflector-supporting ring 2 yieldingly serve to hold the reflector-supporting ring 2 in its 95 fixed adjusted position. The springs 15 between the base 13 and the ring 10 surrounding the screws 14 also yieldingly serve to hold the ring 10 in its adjusted position. In the event a greater range of adjustment 100 is necessary between the ring 10 and the base 13, liner strips, or shims, 17 are inserted as shown in Figs. III and IV between the base 13 and the ring 10. I thus secure a maximum universal adjustment with 105 a minimum amount of movement of the parts to be adjusted in order to secure the proper focal relationship between the bulb, reflector and the headlight lens.

While I have used the term "headlight" 110

herein, I wish it to be understood that my adjusting device is adapted for use in any type of light utilizing a lens and requiring the reflector and bulb to be adjusted with respect to the focal position of such lens. Floodlights and searchlights, for illustration, are intended to be embraced also within the scope of my invention.

I claim:

- 10 1. In a device of the character described, a reflector, a supporting ring for said reflector, ears carried by said supporting ring, screws adapted to pass through apertures in said ears, another ring associated with said reflector-supporting ring and apertured to receive the screws passing through the ears on said reflector-supporting ring, springs surrounding said screws, and means for supporting said last mentioned ring in a lighting device, substantially as described.
- 15 2. In a device of the character described, a reflector, a supporting ring for said reflector, a plurality of ears carried by said supporting ring, screws adapted to pass through 25 apertures in said ears, another ring associated with said reflector-supporting ring and provided with screw-threaded apertures adapted to receive said screws passing through said ears on said reflector-supporting ring, springs surrounding said screws and located between said rings, and supporting means for adjustably carrying both of 30 said rings, substantially as described.

3. In a device of the character described, a reflector, a supporting ring for said reflector, a plurality of ears carried by said supporting ring, screws adapted to pass through apertures in said ears, another ring associated with said reflector-supporting ring and provided with screw-threaded apertures adapted to receive said screws passing through said ears on said reflector-supporting ring, springs surrounding said screws and located between said rings, a support for said second-named ring, screws passing through apertures in said support and adapted to enter screw-threaded apertures in said second-named ring, and springs surrounding said last-named screws and located between said support and said second-named ring, substantially as described.

4. In a device of the character described, a reflector, a supporting ring for said reflector, said supporting ring being provided with openings therein, fastenings adapted to extend through the openings in the supporting ring, a supporting member associated with the reflector supporting ring and adapted to receive the fastenings extending through the openings in the ring, means for providing a resilient backing for the reflector-supporting ring, and means for supporting the supporting member within a lantern.

In testimony that I claim the foregoing I hereunto affix my signature.

GEORGE H. ROLFES.
